United States Patent

Des. 238,594
Patented Jan. 27, 1976

238,594

SAVINGS BOX

Heikki Tavela, 12 Arinatie, 00370 Helsinki 37, Finland

Filed June 18, 1974, Ser. No. 480,491

Claims priority, application Finland May 2, 1974

Term of patent 14 years

Int. Cl. D21—01

U.S. Cl. D34—11 R

FIG. 1

FIG. 1 is a right side elevational view of a savings box showing my new design, the left side being a mirror image thereto;

FIG. 2 is a top plan view thereof;

FIG. 3 is a front elevational view thereof;

FIG. 4 is a rear elevational view thereof;

FIG. 5 is a bottom plan view thereof.

I claim:

The ornamental design for a savings box, as shown and described.
